(57) **CLAIM**

The ornamental design for a container cover, as shown and described.

DESCRIPTION

FIG. 1 is a perspective view of a container cover of the present invention.

FIG. 2 is a top plan view of the container cover shown in FIG. 1.

FIG. 3 is a bottom plan view of the container cover shown in FIG. 1.

FIG. 4 is a front view of the container cover shown in FIG. 1.

FIG. 5 is a left side view of the container cover shown in FIG. 1; and,

FIG. 6 is a perspective view of a portion of the container cover of the present invention.

Broken lines illustrate features or environmental components that are not part of the design sought to be patented.
